UNITED STATES PATENT OFFICE.

MARSHALL R. DOWLIN, OF NORTH ADAMS, MASSACHUSETTS.

HORSE-COLLAR.

SPECIFICATION forming part of Letters Patent No. 254,290, dated February 28, 1882.

Application filed October 22, 1881. (No model.)

To all whom it may concern:

Be it known that I, MARSHALL R. DOWLIN, of North Adams, Berkshire county, Massachusetts, have invented certain new and useful 5 Improvements in Horse-Collars, of which the following is a specification.

My improvement relates to that class of collars which open at the top and are provided with connecting straps; and the invention consists in the construction, arrangement, and combination of the various parts, as more fully hereinafter described and claimed.

In the accompanying drawings, Figure 1 represents a front view of my collar opened at the top; Fig. 2, a similar view closed; Fig. 3, a side elevation of Fig. 2; Fig. 4, a plan view, and Fig. 5 an enlarged cross-section on the line xx of Fig. 2.

The general shape of the collar is the same 20 as usual, a representing the stiff rim, b the body or pad, and d the groove or recess between them for receiving the hame.

The front side, b , is usually formed of a dark leather—such as “patent” or fine leather—25 while the inside or lining c is usually made of a light colored and soft leather to rest against the horse, said inner leather, c , being stitched to the front leather, b , as shown in Fig. 5.

Two layers are generally used to form the 30 front, for the purpose of adding strength to the collar.

The front leather or leathers, $b b'$, are secured at their edges to the edge of the inner leather, c , while they are lying flat one against the other, by a seam on the line e , and the front leathers are then folded back upon the seam, so as to entirely conceal the same, and their outer edges, together with the outer edge of the inner leather, are then brought together and 35 sewed between the edges of the leather tube a , which is of the usual construction. The tubes or cavities thus formed are stuffed in the ordinary manner.

By making the seam e in the manner described it will be observed that the bending of the outer leather over the same not only conceals it, but also forms a smooth round edge to be in contact with the horse, instead of the usual sharp cut edge. This form of seam also 40 allows the use of a strong coarse sewing, or

even of a row of rivets, instead of the usual fine and expensive sewing.

To the top of one of the limbs formed by making the collar open at the top I secure one edge of a broad cap or band, h , which spans the space from one limb to the other, and is secured to the opposite limb by a strap, i , and buckle k . A portion of the sewing fastening the band h to the collar, and also the fastening-buckle k , are so situated that the band will 55 naturally assume the curved appearance of the main portion of the collar.

l indicates the chafe-leather, which is provided with a fastening strap and buckle, $m n$, and is secured to the limb of the collar opposite to the limb to which the band h is sewed, so that the loose ends of the band and chafe-leather will buckle to opposite limbs, so as to 60 make a tighter connection, and also to preserve an even appearance on both sides of the 70 collar.

The cap or band h is made as wide as or wider than the top of the collar, so as to fully cover the opening between the limbs of the same, to prevent the access of water, &c., and also to 75 add to the general neat appearance of the collar.

I am aware that it is not new to provide open-topped collars with caps having sockets or sleeves adapted to fit over one or both ends 80 of the limbs of the collar, and therefore I do not broadly claim such constructions.

What I do claim is—

1. A horse collar constructed with the inner layer or leather, c , and the two outer layers or 85 leathers, $b b'$, secured together, as shown, by a line of stitches or fastening devices, said outer layers being folded away from the inner layer and back upon themselves, covering the fastening-seam, substantially as shown and described.

2. A horse-collar constructed with the inner leather, c , and two outer layers, $b b'$, secured together, as shown, by a line of stitches, said outer layers being folded away from the inner 95 layer and back upon themselves, covering the fastening-seam, and the free ends secured to the rim a by the line of stitches f which form said rim, as specified.

3. In an open-top horse-collar, the strap l , 100

permanently secured to the under side of one limb of the collar, and provided with straps to secure it to the under side of the opposite limb, in combination with the broad cap-band *h*, permanently secured to the upper part of the limb opposite to that to which the strap *l* is permanently fastened, and provided with a strap to secure it to the upper part of the latter limb,

both the fastening devices of the cap-band being arranged in the hame-recess of the collar, substantially as described, and for the purpose specified.
